DESIGN FOR A SLIPPER OR SIMILAR ARTICLE

Kenneth Keyes, New York, N. Y.

Application April 12, 1946, Serial No. 128,502

Term of patent 7 years

(Cl. D7—7)

To all whom it may concern:

Be it known that I, Kenneth Keyes, a citizen of the United States of America, residing in New York, county of New York, and State of New York, have invented a new, original, and ornamental Design for a Slipper or Similar Article, of which the following is a specification, reference being had to the accompanying drawing, forming part thereof.

Fig. 1 is a front perspective view of a slipper or similar article showing my new design.

Fig. 2 is a rear perspective view thereof.

My design for a slipper of the specific type as shown is characterized by a transparent strap across the center thereof, said strap being narrow at the center and widening to the points of contact with the sole portion, the outer edges of the strap being ornamented on both sides in a manner as illustrated.

I claim:

The ornamental design for a slipper or similar article, substantially as shown and described.

KENNETH KEYES.
